CLAIM

The ornamental design for a cutting board, as shown and described.

DESCRIPTION

FIG. 1 is a top perspective view of a cutting board showing my new design;

FIG. 2 is a bottom perspective view thereof;

FIG. 3 is a right side elevational view thereof with the left side being a mirror image of the right side; and,

FIG. 4 is a front elevational view thereof with the rear elevation being a mirror image of the front elevation.

1 Claim, 1 Drawing Sheet

FIG. 1

FIG. 2

FIG. 4
